DESIGN FOR A LIFE PRESERVER

Milton Paul Lindsay, Providence, R. I.

Application October 29, 1936, Serial No. 65,578

Term of patent 3½ years

To all whom it may concern:

Be it known that I, Milton Paul Lindsay, a citizen of the United States, residing at Providence, in the county of Providence and State of Rhode Island, have invented a new, original, and ornamental Design for a Life Preserver, of which the following is a specification, reference being had to the accompanying drawing, forming part thereof.

The figure is a perspective view of a life preserver showing my new design.

I claim:—

The ornamental design for a life preserver as shown.

MILTON PAUL LINDSAY.
